AUTOMATIC WIRE TYING MECHANISM

Fred J. Trimble, Maywood, Calif., assignor to
The American Brake Shoe and Foundry Company, Wilmington, Del., a corporation of Delaware

Application February 6, 1934, Serial No. 709,957

14 Claims. (Cl. 100—20)

This invention relates to an apparatus for tying wires such as baling wires and for the sake of convenience I have shown my wire tying apparatus associated with a baling press wherein a plurality of baling wires are automatically tied about a bale of hay when the same has been formed; but it is to be understood that my wire tying apparatus or mechanism may be used for tying a single or a plurality of wires about other articles, packages or boxes.

An object of my invention is to provide a simple, novel, efficient and compact mechanism for tying wire, such as baling wire, about an article, as for example, a bale of hay, or the like.

An object is to provide novel wire tying mechanism which is simple and of such compact character that a plurality of wires may be simultaneously tied about an article, bundle or package to be tied.

An object is to provide novel wire tying mechanism that may be associated with hay balers whereby a plurality of wires may be automatically tied about a bale of hay when such bale has been formed by the hay baler to a predetermined length or density.

Another object is to provide novel and simple mechanism whereby the free ends of a wire encircling an object may be securely tied or twisted together into a knot or about each other without leaving the free ends of the wire projecting from the twisted portions.

Another object is to provide a simple, compact, efficient and novel mechanism whereby an object may be forced against strands of wire that extend from spools or reels of such wire and the ends of which have been tied together, so that such wire will encircle three sides of such object, and to then bring such strands of wire tautly around such object and cut the wires and tie the free ends thereof together so as to leave a wire encircling such object and at the same time tie the free ends of the wires from the supply spools or reels together so as to present a united strand of wire against which a subsequent object may be forced.

A still further object is to provide novel means for taking wire from supply spools and binding therewith each article to be bound, severing the wire, and then tying the free ends of the wire about the article to be bound, and at the same time tying together the free ends of the wires from the supply spools and leave such wire in position to be bound around another article.

A still further object is to provide novel wire

tying mechanism of the above character which will cut the wire to be tied about an article, and efficiently tie or twist the free ends of the wire together without clipping off a portion of the wire strand that may contaminate the article being tied or clog the mechanism.

The invention includes in addition to the parts and combinations of parts, the novel means for tying the free ends of wires about an article to be tied and at the same time tying together the free ends of strands of wire from separate supply spools so as to enable such wire to be engaged by and tied around, a succeeding article to be tied.

Other objects, advantages and features of invention may appear from the accompanying drawings, the subjoined detail description and the appended claims.

The accompanying drawings illustrate the invention as applied to a hay baler and illustrate my novel wire tying mechanism in the form I at present deem preferable.

Figure 1 is a side elevational view of a baling press provided with my wire tying mechanism or apparatus and with the stoking element in the down position and the wire tying apparatus in inoperative position.

Figure 2 is an enlarged detail sectional view taken on line 2—2, Fig. 1, but showing the mutilated helical gear rotated from the position shown in Fig. 1, so as to more fully disclose the operative relation of the parts.

Fig. 3 is a transverse sectional view on line 3—3, Fig. 11, showing the wire tying mechanism in withdrawn or retracted position, and showing the operating mechanism for moving the wire tying elements into tying position. Parts are broken away to contract the view and to disclose parts otherwise hidden.

Fig. 3a is a sectional view on line 3a—3a, Fig. 40, showing the drive connection for the wire tying fingers.

Fig. 4 is an enlarged sectional detail view taken on line 4—4, Fig. 3.

Fig. 5 is a fragmentary detail view taken on irregular line 5—5, Fig. 3. The control cam of the trip mechanism having been rotated to a position where it is about to release associated parts to permit operation of the wire tying mechanism.

Fig. 6 is a fragmentary plan detail view of the control cam of the trip mechanism in position just after release of the operating mechanism for the wire tying elements so as to permit operation of the wire tying mechanism.

Fig. 7 is a view analogous to Fig. 6 but with the control cam rotated to an intermediate position between that shown in Figs. 5 and 6 to illustrate one cam on the control cam, and in which position the wire tying mechanism is in retracted position.

Fig. 8 is a face view of the control cam as viewed on line 8—8, Fig. 7 and looking in the direction of the arrows.

Fig. 9 is a fragmentary transverse sectional view taken on a plane indicated by irregular line 9—9, Fig. 3, and showing the wire tying mechanism in retracted position. Parts are broken away to contract the view, and dotted lines indicate the united ends of the wire strands partially extended along the press box, as by a contacting article, not shown.

Fig. 10 is a fragmentary longitudinal sectional view of the press box, and associated parts, and showing the operating mechanism for the wire tying mechanism in position just previous to being moved into position for a wire tying operation. The compression plunger having been moved to retracted position, and not shown.

Fig. 11 is a fragmentary longitudinal sectional view with the compression plunger in its extreme forward position and with the operating mechanism in position to commence a wire tying operation.

Fig. 12 is a fragmentary view of the operating mechanism analogous to the lower part of Fig. 11, but with the parts in position after a wire tying operation has been completed and just previous to the operating mechanism for the wire tying elements being withdrawn from operating position.

Fig. 13 is a fragmentary sectional view on line 13—13, Fig. 11.

Fig. 14 is a fragmentary sectional view on line 14—14, Fig. 11, and looking in the direction of the arrows.

Fig. 15 is a fragmentary sectional detail view in plan and taken on line 15—15, Fig. 12.

Fig. 15a is a detail edge view of the operating cam members for the wire tying mechanism, as viewed on line 15a—15a, Fig. 12.

Fig. 16 is a fragmentary longitudinal sectional view partly in elevation, showing the means for operating the trip mechanism.

Fig. 17 is a fragmentary transverse sectional view taken on line 17—17, Fig. 16, and showing a fragment of a bale of hay.

Fig. 18 is an enlarged fragmentary plan view of the wire tying mechanism and in position to commence a wire twisting operation.

Fig. 19 is an edge elevational view of the parts shown in Fig. 18.

Fig. 20 is a sectional view of the parts shown in Fig. 18, as taken on line 20—20, Fig. 18.

Fig. 21 is a transverse sectional view taken on line 21—21, Fig. 19.

Fig. 22 is a detail view of the compression plunger, partly in plan and partly in section.

Fig. 23 is a more or less diagrammatic perspective view of the wire twisting fingers and in position shortly after a wire twisting operation has commenced.

Fig. 24 is a perspective view of the knot or wire tie formed by my wire tying mechanism.

1 designates a baling-press of ordinary or preferred type, consisting in the present instance of a press-box or baling case 2, having a feed opening 3, a hopper 4, an adjusting device 5 for regulating the density of the bales, a driven cog wheel 6, a compression plunger 7 connected to the cog

wheel 6 by pitman 8, and a stoker 9 connected to cog wheel 6 by a walking beam 10 and link 11. The press 1 is also provided with the carrying-wheels 12 and driving pulley 13, to which power is transmitted over the belt 14 from any suitable source, said pulley 13 being connected in any suitable manner to drive cog wheel 6 at the proper speed.

The cog wheel 6 is fixed to shaft 15 to which a mutilated helical gear 16 is fixed by a key 17 and such gear 16 meshes with a pinion 18 fixed to one end of shaft 19 journaled in bearings 20 that extend from the frame 21 of the press. A bevel gear 22 is fixed to the other end of shaft 19 and is in mesh with a bevel gear 23 fixed to shaft 24 and thereby provides power to drive the mechanism connected to shaft 24 as hereinafter explained.

The pinion 18 is provided with a slot 25 in which a tooth 26 on gear 16 is received to lock the shaft 19 in a predetermined position so that operation of the mechanism connected to shaft 24 is obtained only at predetermined timed relation and intervals relative to the cog wheel 6 and its associated plunger 7 and stoker 9, and thereby with the helical gear portion 27 on gear 16 cooperating with the pinion 18 I obtain a locked intermittent motion relative to such plunger and stoker.

28 designates a pair of spools mounted in a pair of brackets 29 secured to the side of a baling-case. A plurality or a pair of spools 28 and a plurality or a pair of brackets 29 are mounted on each side of the baling-case, and it is to be understood that a spool is mounted on opposite sides of the baling-case for each wire to be tied about an article. Said spools carry wires 30 from which the bale-ties for binding the articles or bales are cut. The free ends of each of said wires from opposite spools are run through or around a guide member 31 (see Fig. 9) and through the wire twisting members as herein-after described and thence transversely through the press-box where they are joined together in a secure knot.

The material a to be compressed is inserted into the hopper 4 from which stoker 9 forces the same into compression chamber 32 and is operated upon in the usual manner by the compression plunger 7 and forced along such chamber 32 in the direction of the arrow 33 (Fig. 9) toward the discharge end 34 of the press box.

As the bale is forced along the press box it comes into contact with the tined chain 35 (Figs. 16 and 17) which is trained around sprocket wheels 36, 37 respectively mounted on shafts 38—39 journaled in bearings 40, 41 secured to the frame 21. The shaft 39 has a worm gear 42 fixed to one end thereof and in mesh with a worm wheel 43 that is fixed to shaft 44 journaled in a suitable bearing 45. Shaft 44 is extended along the frame 21 underneath the press box through chamber 46 formed by the housing 47 connected to frame 21 and which housing encloses the operating mechanism mounted therein and protects the same from foreign elements. At the other end of shaft 44 a bevel gear 48 is fixed thereto which is in mesh with bevel gear 50 fixed to shaft 51 mounted in bearing 52 and the shaft 51 is connected to drive shaft 53 by bevel gears 54 secured to shafts 51 and 53.

A control mechanism A including an intermittently operated member 55 fixed to shaft 53 and provided on its face 56 with a cam recess 57 and a raised cam portion 58, the actions and op-

erations of which will be hereinafter described.

From the foregoing it will be seen that as a bale of hay is progressively formed or pressed in the press box by the progressive action of the 5 stoker and plunger, that the tined chain 35 will be engaged by such bale or hay as it is forced along the baling chamber 32' and through the mechanism associated with the chain 35 the cam member 55 will be intermittently rotated so as to 10 present the cam portions thereon relative to its associated trip mechanism at predetermined points relative to the length of the bale of hay formed in the baling chamber.

The cam member 55 has associated therewith 15 cooperative trip mechanism which is subject to the control of cam member 55 and includes a sliding bar 60 mounted in guides 61 that are secured to transversely extending I-beams 62 of the frame 21. An extensible spring 63 is 20 secured at one end to bar 60 and at its other end to the framework 21 and tends to normally urge or pull the sliding bar 60 and the contact finger 64 which is secured to sliding bar 60 in a direction so that the free end of contact finger 64 25 engages the flat surface or face 56 of cam member 55 and forces such contact finger into the cam recess 57 when such recess 57 presents itself to permit such operation, as is shown in Fig. 11.

As the sliding bar 60 is moved by spring 63 upon the contact finger 64 entering the cam recess 57 such movement will also move the bell crank 65 that is pivoted at 66 to the slide bar 60 along with the slide bar 60 so as to position the 30 free end 67 of bell crank 65 that is provided with a roller contact point 68, in position to be acted upon by cam 69 as hereinafter set forth. One end of bell crank 65 is forked and provided with rollers 70 which are received in a groove 71 formed on the slidable operating cam member 72.

When the contact finger 64 is received in recess 57 the slide bar 60 is moved by spring 63 to position the roller contact 68 in the path of, and to be engaged by cam 69.

As the helical gear portion 27 on gear 16 is 45 moved by the driving pulley 13 it will engage pinion 18 and operate shafts 19 and 24 which latter shaft 24 is connected by bevel gears 73 to operate shaft 74 mounted in suitable bearings in frame 21 and which is connected by bevel gears 50 75 to operate shaft 76 to which cam 69 is fixed.

The cam 69 is constructed to operate during a one-eighth revolution of shafts 74 and 76 and the helical gear portion 27 and pinion 18 and connecting bevel gears 22, 23, 73 and 75 are constructed to rotate the shafts 74 and 76 a complete revolution during engagement of the gear portion 27 with pinion 18.

When the slide bar 60 has been moved by 60 spring 63 as before stated after contact finger 64 has entered recess 57 the cam 69 will engage the roller contact point 68 and move bell crank 65 about its pivot 66 and also move the slidable operating cam member 72 along shaft 74 to which it is rotatably related by means of the sliding key fit 77. Such movement of member 72 along shaft 74 is against tension of a compression spring 78 that is weaker than spring 63.

As operating cam member 72 is moved along shaft 74 by depressing bell crank 65 by cam 69 the parts are correlated so that a recess 79 in a collar 80 is presented to permit such collar 80 to be moved from one side of a retaining member 81 to the other side thereof where a roller 82 on member 81 engages collar 80 to prevent retraction 75

of the operating cam member 72 until its operation has been completed and to also relieve strain on bell crank 65 and release such bell crank and slide bar 60 for further operation to permit the slide bar 60 to be returned to position 5 where bell crank 65 will be held out of operative contact with cam 69 before the cam member 72 has completed its operation.

The return of slide bar 60 against tension of spring 63 is accomplished by a cam tapered lug or 10 projection 83 on member 72 coming into contact with roller 84 on one end of lever 85 which is pivoted at 86 to a support 87 that is fixed to frame 21. The other end of lever 85 is extended to engage a stop or lug 88 fixed to slide bar 60, so that 15 as member 72 is rotated by shaft 74 the projection 83 will engage roller 84 and move lever 85 about its pivot and force slide bar 60 along its bearings so as to bring contact finger 64 out of recess 57. 20

A spring 88' tends to normally keep the lever 85 in contact with lug 88 and to keep the roller 84 out of contact with cam 83 until such cam 83 is required to operate upon lever 85.

In the trip mechanism, when the contact finger 25 was first received in the recess 57, a slide bar retaining member 89 pivoted intermediate its ends at 90 to retaining finger 64, is at right angles to such finger 64, as shown in Fig. 5. At one end of member 89 is an upstanding portion 30 that contacts (as hereinafter described) with the face 56 and raised cam portion 58 of cam member 55, all within the radius of such face 56 contacted by finger 64. The retaining member 89 is provided with an upstanding pin 92 which when 35 the retaining finger 64 is received in recess 57 is moved past the tapered free end 93 of spring 94 (see Fig. 6) which is fixed to the frame 21.

The other end of member 89 is pivotally connected to one end 95 of a toggle connection 96 40 which is actuated by spring 97 encircling rod 98 that has a sliding connection with post 99 fixed to a support 100 that extends from or is secured to frame 21.

As the slide bar 60 is moved against the tension of spring 63 by lever 85 and cam 83, and contact finger 64 is withdrawn from recess 57 by such movement, the pin 92 will engage the flattened free end 101 of spring 94, and thereby move member 89 about its pivot until its other end has been moved past dead center and the snap action of the toggle connection 96 will move member 89 into parallelism with finger 64 as shown in Figs. 7 and 12, so that upon release of the retractive movement of slide bar 60 by disengagement of roller 84 and cam 83 the upstanding portion 91 of retaining member 89 will engage the face 56 of cam member 55 and prevent contact finger 64 from again entering recess 57 until such recess has been moved a complete revolution by a subsequent bale contacting the tine chain 35 and thereby moving its associated mechanism. 50 55 60

However, as such subsequent bale moves the tined chain 35 and its associated mechanism to 65 rotate cam member 55, the raised cam portion 58, after the recess 57 is moved to prevent contact finger 64 from entering recess 57, will engage the upstanding portion 91 of retaining member 89, during rotation of cam member 55, and force 70 such retaining member 89 about its pivot 90 until the toggle connection 96 will actuate the member 89 to assume its position at right angles to the contact finger 64 as shown in Figs. 5, 10 and 11, and at which instant the contact finger 64 will 75

engage the face 56 of cam member 55 and prevent movement of slide bar 60 until the recess 57 has again presented itself to finger 64 after which the operation hereinabove described as pertaining to said parts will be repeated.

The operating cam member 72 is provided with opposed cam surfaces 102, 103 that engage roller supplied free ends 104, 105 of bell cranks 106, 107, pivoted at 108, 109 to frame 21 and the other ends of which bell cranks are connected at 110, 111 to move the wire tying elements into wire tying position.

The bell cranks 106, 107 are connected to one end of adjustable rods 112, 113 at 110, 111 and the other ends of said rods are connected to levers 114, 115 that are pivoted intermediate their ends at 116, 117 to supports 118, 119 that extend from opposite sides of frame 21. The levers 114 may extend below supports 116, 117 and be connected to springs 120, 121 that extend from supports 118, 119 and normally urge the levers 114, 115 to a retracted position and maintain the roller ends 104, 105 of the bell cranks 106, 107 in engagement with the cam surfaces of the cams 102, 103.

Levers 114, 115 are connected to cross-bars 122, 123 through pivotally connected links 124, 125 and one or a plurality of complementary wire tying elements 126, 126' may be connected to each cross-bar 122, 123, as desired. In this respect, one element 126 and one element 126' are reciprocably mounted on opposite sides of the baling chamber 32' or on opposite sides of a passageway 32' in which the article or bundle to be tied is moved so as to engage the wire strand or strands that extend across such passageway, as shown in Figs. 3 and 9.

As the construction of each wire tying element 126, 126' is identical, except for the fact that the elements 126' are mounted inversely to the mounting of the elements 126, only one element will be described in detail for the sake of brevity and like characters will be applied to like parts. By reason of making the complementary elements identical in construction and merely mounting one element on one side of the passageway inversely to the mounting of the element on the other side of such passageway I thereby simplify the construction of my invention.

The wire tying elements 126, 126' include carrier members 127 each of which has a T-plate 127' secured to one side thereof by bolts 128 and the extending arms or ribs 128' of T-plate 127' are slidably mounted in guideways 129 formed by plates 130 secured by screws 131 to a supporting member 132 that is fixed by bolts 133 to a plate 134 that is secured by bolts 135 to upright angle-irons 136, 136' that form part of a framework 137 that is built-up on each side of the passageway 32' from frame 21 to support the wire tying elements in proper position. Bearing plates 138 are secured by bolts 139 to uprights 136 and by bolts 140 to plate 134. A shaft 141 is slidably extended through each bifurcated lug 142 of bearing plate 138 and such shaft has a splined connection with a driven spiral gear 143 that is mounted between the lugs 142 and such gear 143 is in mesh with a driving spiral gear 144 which is fixed to shaft 145 mounted at one end in bearing plate 138. The other end of one shaft 145 is provided with a bevel gear 146, in mesh with bevel gear 147 (see Figs. 3 and 5) that is fixed to shaft 148, mounted in bearing 149 which extends from frame 21. Shaft 148 is driven by means of bevel gears 150, shaft 151 mounted in bearings 152, 75 bevel gears 153, shaft 154, bevel gear 155 in mesh

with bevel gear 156 that is fixed to one end of shaft 157 that is provided at its other end with a stub gear 158 and collar 159 and which gear 158 is engaged by a mutilated gear portion 160 and collar 159 is received in a recess 161, both 5 formed on operating cam member 72.

A suitable gear drive 162, (Fig. 3a) is provided to drive shafts 141 in unison from the single driving power applied to either of shafts 145.

The cross bars 122, 123, are connected to the 10 carrier member 127 in any suitable manner as by the bifurcated lugs 163 that straddle member 127 and are riveted or bolted thereto.

Each of the shafts 141 are mounted in bearings 164 fixed to each end of carrier member 15 127 and are provided at one end with a gear 165 and at its other end with a collar 166 and such gear 165 and collar 166 maintain the shaft 141 in longitudinal relation to the carrier 127.

Rotatable sleeve shafts 167, 167' are mounted 20 in bearings 168, 168' fixed on each of the carriers 127 and at the inner end thereof. The sleeves 168' which are on the side of carrier 127 to which the article to be tied is moved to tying position, are open sided or provided with slots 25 169. A gear 170 is fixed to one end of the sleeve shafts on one side of its respective bearing 168 and the other end of the sleeve shafts are provided on the other side of bearing 168 with wire engaging and twisting fingers 171 that are forked 30 as at 172, and the innermost finger 172' is raised from the periphery of the member from which it is formed so that it protrudes from such periphery so as to pick up the wires, as hereinafter explained.

The gears 170 and fingers 171 maintain the sleeve shafts in longitudinal relation to its bearing 168, and the gears 170 are in mesh with gears 165 which rotate the sleeve shafts there-with.

At the inner or free end of carrier member 127 a wire engaging and tensioning plate 173 is slidably mounted on shoulder bolts 174 that extend through slots 175 into carrier member 127. A spring 176 operating between a stop or lug 177 extending from member 127, and an upstanding end 178 on plate 173, tends to normally urge said plate 173 toward the free end of member 127. The spring 176 is carried on and encircles a pin 179 that is fixed to the upstanding end 178 of plate 54 173 by nuts 180, and such pin has a slide fit in lug or stop 177. The plate 173 is provided at its end opposite the upstanding end 178 with a wire engaging surface 181 in the form of an upstanding end of plate 173.

A wire cutting knife 182 is fixed to carrier member 127 by bolts 183 and extends through the upstanding wire engaging end 181 of plate 173 when such plate 173 is moved against tension of spring 176, as hereinafter explained. The knife 182 cooperates with a shearing edge 184 formed in the opposite complementary wire tying carrier member 127, and severs the baling wire 30 when the wire tying elements are brought together as shown in Figs. 18-20.

At the free end of the carrier member 127 I also provide wire engaging and angling rollers 185 which are preferably four in number pivotally mounted on axes 186 formed by bolts that extend through plates 187 mounted on and secured to opposite sides of the free end of carrier member 127 by a plurality of bolts 188. The rollers 185 are preferably arranged so that two of such rollers are offset from the longitudinal sides of member 127 so that their peripheries will be 75

tangent to the axes of sleeve shafts 167 that are provided with openings 189, 189' through which the wires 30 are extended. The opening 189' is open sided or slotted as at 190 analogous to the 5 slotted or open sided bearing 167'. And when the carrier members 127 are brought together the said offset rollers on complementary carriers are in juxtaposition relative to each other. The other rollers 185 are in spaced relation lengthwise of the carrier members 127 relative to said offset rollers and the plates 187 are notched as at 191 to form an opening in which finger 172' may travel to engage and pick up the wire 30 that has been run around rollers 185 and by reference to Fig. 18 it will be seen that such wire 15 30 will extend from the offset rollers around the lengthwise spaced rollers and across the notched portions 191 at substantially a forty-five degree angle relative to the longitudinal medial axis of 20 carrier member 127 or shafts 167.

The compression plunger 7 is preferably provided on opposite sides with slide guide projections 192 that are received in slots and guideways 193 formed on each longitudinal side wall 194 of 25 the compression chamber 32. Rockably mounted in plunger 7 are a plurality of members 195 that have rollers 196 secured to opposite ends thereof and which rollers 196 are mounted in the cam grooves or slots 197 formed in side wall 194. A 30 dog nose screw 198 extends from the rear of plunger 7 into a groove 199 formed in rockable members 195 and tends to retain members 195 in plunger 7 and also form a stop for limiting oscillation of members 195. The members 195 35 are each provided with a groove or slot 200 that extends throughout the length of the member 195 and coincides with an opening 201 in back side wall 194 when the plunger 7 has been moved to its foremost compressing position, and the wire tying elements are inserted through opening 201 and slot 200 when the plunger has reached the 40 end of its compression stroke and a wire tying operation is desired.

The members 195 extend through the face 202 of plunger 7 and the openings 200 are slotted as 45 at 203 so as to expose said openings 200 through the face of plunger 7 to the baling chamber 32' when the plunger is at its foremost position.

It will be seen that as the plunger 7 is reciprocated by pitman 8 that the rollers 196 operating in grooves 197 will oscillate members 195 through the cam action of such rollers 196 and the inclined or cam surfaces 204 in grooves 197 so that when the plunger 7 is in rear of such cam 55 surfaces 204, the members 195 will close the face of the plunger 7 and thereby present a solid surface which will operate upon the hay to be compressed, until the plunger has nearly reached the end of its compression stroke when the cam surfaces 204 acting upon rollers 196 will oscillate or 60 rock members 195 into the position shown in Fig. 11. It will be understood that the length of the straight portion 205 of groove 197 will determine the length of time the slots 203 are presented to the face of the plunger, and if such portions 205 are shortened the slots 203 will be 65 presented to the baling chamber 32' only throughout a very short space of time.

By reference to Figs. 9, 10 and 11 it will be 70 seen that I have provided the baling chamber 32', at the point where the plunger 7 reaches the end of its compression stroke, with a chamfered or beveled edge 206 that flares outwardly from the compression chamber 32, in which the plunger 75 75 operates. This beveled edge 206 slightly in-

creases the cross-sectional area of the baling chamber 32' from the compression chamber 32 and will permit hay forced into the baling chamber 32' by plunger 7 to slightly expand and when the plunger 7 is retracted the hay in baling chamber 32' will engage such beveled edge 206 and thus tend to prevent its material bulging back into compression chamber upon withdrawal of the plunger from the hay preparatory to another compression stroke.

In operation the wire strands from spools 28 are first threaded through the guides 31 and thence through the sleeve shafts 167 that are provided with the slotted openings 189 thence across the compression chamber 32 where they are at 10 first tied together by hand, so as to present a 15 united strand of wire that extends across the passageway in which the article to be tied is moved. Thereafter as the article to be tied is moved along the passageway 32', such as by the 20 compression of hay by the compression plunger 7 into a bale of hay, the wire strands 30 will be forced around three sides of the bale of hay, or article to be tied, and will assume the position shown in dotted lines in Fig. 9, and as the wire 25 30 from the spools of wire 28 is unwound therefrom, the same will be under a predetermined tension, occasioned by tensioning means not shown, and it will be noted that the wire will extend across the notched portions 191 in plates 30 35 187, as indicated in Fig. 18, and in dotted lines in Fig. 9. As the bale of hay is moved toward the delivery end of the hay baler the tine chain 35 will be moved, as hereinbefore indicated, so that when the bale of hay has reached a predetermined length the recess 57 on cam member 55 will be presented to permit operation of the slide bar 60, as hereinbefore stated, and the mutilated gear 26 is positioned relative to the shaft 15 so that the helical gear portion 27 thereon will operate pinion 18 only when the compression plunger 7 has approximated the end of its compression stroke. In other words, when the gear portion 27 40 has engaged pinion 18 so as to rotate pinion 18 a full turn the compression plunger 7 will be at its 45 extreme forward position so that as the pitman 8 is going over its dead center at such position the pinion 18 will be rotated; and thereby only slight, if any, reciprocal movement of plunger 7 will be obtained during rotation of pinion 18. 50

After the slide bar 60 has been operated, as hereinbefore stated, engagement of gear 27 with pinion 18 will rotate the operating cam member 72 one complete revolution and at the commencement of such revolution the cam 69 will be positioned so as to just commence its engagement with roller contact 68 of bell crank 65, and throughout the first one-eighth movement of operating cam member 72, bell crank 65 will be moved about its pivot 66 to force operating cam 60 member 72 along shaft 74 as hereinbefore stated.

This slideable movement of member 72 on shaft 74 will position the opposed cam surfaces 102 and 103 in position to engage the ends 104, 105 of bell cranks 106, 107 and further rotation of member 65 72 will depress the free ends of bell cranks 106, 107 against tension of the springs 120, 121, so as to move the complementary wire tying elements toward each other until such elements assume the positions shown in Figs. 18-20; and at which 70 position of member 72 on shaft 74, the mutilated gear portion 160 on member 72 will engage the stub gear 158 and the ratio between such gears 158 and 160 is such that the sleeve shafts 167 will, through their intermediate gear connections 75

with gear 160, be rotated a sufficient number of times to effectively complete the wire twisting and tying operation. In this respect, the recess 79 in collar 80 and the opposed cam surfaces 102, 103 and the mutilated gear 160, all on cam operating member 72, are so co-related to each other that during the first one-eighth revolution of such cam member the cam member 72 will be moved along shaft 74 to bring such parts thereon into operative relation with stub gear 158 and with ends 104, 105 of the bell cranks 106, 107 and during the next one-fourth revolution, the wire tying elements will be moved inwardly toward each other, then during the next one-fourth revolution of cam member 72 the sleeve shafts 167 will be rotated and during such operation of sleeve shafts 167 an idle or dwell portion is formed on cams 102, 103 to prevent further reciprocal movement of the wire tying elements, and then during the next one-fourth revolution of member 72 the wire tying elements will be withdrawn from their extended position across the passageway 32, and then during the next one-eighth revolution the member 72 will be moved along shaft 74 by operation of spring 78, and during such last operation the retaining member 81 will be passed through recess 79 in collar 80 and thereby withdraw the cams 102, 103 from engagement with bell cranks 106, 107 and withdraw the mutilated gear 160 from the path of engagement with the stub gear 158, so that further operation of shaft 74 by engagement of the mutilated gear portion 27 with pinion 18 may rotate operating cam member 72 without effecting operation of the wire tying elements.

When the member 72 has been moved along shaft 74 into operative position and the wire tying elements have been moved toward each other so that they assume the position shown in Figs. 40 18-20, such movement of the wire tying elements transversely of passageway 32 will occasion the wire 30 that has encircled the bale of hay, or article to be tied, to be engaged by certain of the rollers 185 so that such wire is extended from the wire supply spool around the end of one complementary wire tying element and over the rollers 185 carried thereby, and thence along the longitudinal side of the wire tying element and around the bale of hay. In other words the wire tying element when moved to wire tying position will form a U-loop b in the wire between its source of supply and the article to be tied and at the base c of such loop the wire will be extended across the notched portions 191 so that the wire 50 will lie at substantially a 45° angle d to the upper right sides e forming the U-loop b in the wire.

As the wire tying elements reach a position so that their ends are adjacent each other in slightly overlapped position, as shown in Fig. 20, the plate 173 on one member will engage the wire extended around the free end of the complementary wire tying carrier member 127 and frictionally hold such wire between its upstanding and/or wire engaging surface 181 and the end of the wire tying element carrier member 127. Further movement of the wire tying carrier members 127 toward each other will cause the knife 182 to engage the wire 30 and cut the same on the shearing edge 184, as shown in Fig. 18.

After this wire looping, engagement and cutting operation has been performed, the mutilated gear 160 becomes engaged with the stub gear 158 and the sleeve shafts 167, 167' rotated by means of the driving power applied to gears 170 by the gears 165, will rotate the extended fingers 172'

and such fingers 172' will travel in the notches 191 and pick up the wire extended at an angle thereacross and twist the free ends thereof around each other until such free ends have been completely twisted or wrapped around each other in the manner shown in Fig. 24.

The tension plate 181 retains the free ends of wire 30 under tension so that the wire twisting or tying fingers will effectively and efficiently twist the ends together in a tight knot. As the wire 30 when it is picked up by the extending fingers 172' is forced into the notches 172 the wire is extended away from the free ends of the fingers 171 and due to that fact and the relative stiffness of the wire the free ends will be completely wrapped or twisted around an opposing wire without leaving free ends thereof protruding from the knot.

As the wire tying elements are removed from cooperative position with each other a strand of wire has been tied about the article to be tied and a strand of wire is left extending across the passageway in position to be engaged by a succeeding article to be tied.

From the foregoing it will be seen that it is not necessary to slot the sleeve shaft 167 or its associated bearing and gear 170, because such elements merely ride over the extended wire 30 from its supply spool, but the sleeve shaft 167' and its associated bearing 168' and gear 170 30 and which are adjacent the article being tied are slotted, as at 169 and 190, so as to permit the wire tied about the article or bale of hay to be withdrawn from the wire tying elements when the tied article is removed.

It will also be seen from the foregoing that the compression plunger 1 is at the end of its compression stroke when the wire tying elements have been moved to wire tying position, and the rockable members 195 have been moved, by their associated rollers 196 engaging cam grooves or slots 197, into the position shown in Fig. 11 so as to enable the wire tying elements to be passed thereto, and the ends of the wire that have been united from the supply spools as just recited will pass through the openings 200 and slots 203 as the compression plunger is reciprocated to the beginning of its compression stroke.

From the foregoing it will be seen that during a wire tying operation, I cut the wire from supply spools and tie the free ends of such wire about an article to be tied, and also at the same time tie together the ends of such wire from the supply spools so as to form a united and connected strand of wire that extends across a passageway along which an article to be tied is moved, and all of such wire tying operations, as in the case of the hay baler herein illustrated, are accomplished within the compression plunger of the hay baler.

It will be apparent that if the compression plunger and the rockable members 195 mounted therein are made of greater thickness so that the longitudinal slots 200 formed in members 195 may be of greater width than that shown, the accuracy in timing need not be so precise because if such slots 200 are of greater width the plunger may override the gears for a distance equivalent to the width of the slots 200 without danger to the inserted mechanism.

The slots in the sleeve shafts 167' and bearing 168' are so gear related that the sleeve shaft 167' will always come to rest with its slot 190 in juxtaposition to the slot 169 in its associated bearing, and the slot in the gear 170 associated 75

therewith is preferably at the root of a gear tooth so as not to interfere with uniform and accurate operation of co-related gears.

The means that is provided for causing the sleeve shafts 167' to come to rest with its slot 190 in juxtaposition to the slot 169 in its associated bearing 168' is that the collar 159 which is in fixed relation with shaft 157 is provided with an arcuate portion 299 that fits the periphery of the cylindrical member 298 of cam operating member 72, and on which the mutilated gear portion 160 is formed, and in which recess 161 is provided, so that when the operating cam member 72 is moved by bell crank 65 into operating position, and the gear portion 160 engages the stub gear 158, the collar 159 will be received in, and be free to rotate in the recess 161, and as soon as the mutilated gear portion 160 is out of contact with stub gear 158 the arcuate recessed portion 299 will coincide with the periphery of the cylindrical member 298 and thereby lock shaft 157 and its associated parts against rotation until the mutilated gear portion 160 is again moved into position to contact and rotate the stub gear 158.

From the foregoing it will be seen, and particularly by reference to Figs. 18-20 and 23, that the wire tying carrier members when moved toward each other are brought into abutting and overlapping relation with respect to the free ends thereof and such wire tying carrier members will move the loop of wire *b* so that each respective base *c* of such loop will be extended beyond each other thereby crossing the wires from opposite supply spools so that the free ends thereof, after the same have been cut by the knife 182, will be positioned in overlapping relation relative to each other and the extended wire tying pick-up fingers 172' on one wire tying member 127 will pass through the notches 191 formed on the opposite wire tying carrier member and pick-up the wire angled as at *d* across such notched portions 191 on the opposite wire tying carrier member 127 so that when the free ends of the wire from the wire supply spools are twisted about the upright sides *e* which form the U-loop *b* the wire strands 30 will be extended across each other and then twisted therearound into the position shown in Fig. 24.

I claim:

1. In a wire tying device, slidably mounted carrier members adapted to be brought into abutting and overlapping position at the cooperative ends thereof; wire tying fingers rotatably mounted on said carrier members; means for rotating said wire tying fingers; the ends of said carrier members being provided with notched portions across which a wire to be tied is angularly positioned when said carrier members are moved into abutting position; and said wire tying fingers being adapted to rotate in such notched out portions and pick up said angularly disposed wire and twist the same together.

2. In a wire tying device, complemental slidably mounted carrier members; wire tying fingers rotatably mounted on said carrier members; means to extend a wire across the free ends of said carrier members; and means to move said carrier members toward each other so that the wire extended across the end thereof will overlap the wire extended across the end of its complemental carrier member; means to cut said wire upon the bringing together of said complemental carrier members; and means for rotating said wire tying fingers to twist the free ends of said wire together.

3. In a wire tying device complemental slidably mounted carrier members adapted to be moved into cooperative wire tying position; a supply of wire for each carrier member; means on each member to engage and retain a portion of said wire about the free end of said member when said members are moved to wire tying position; means to cut the wire at the free end of said members; and means on each of said members to engage a cut wire of its complemental member to twist abutting cut wires together.

4. In a device for tying wire, a plurality of slidably mounted carrier members; a plurality of sleeve shafts on each member; means connected to rotate said shafts; wire tying fingers on said shafts; wire supply reels having a wire strand extending through certain of said sleeve shafts and having their free ends joined together and adapted to encircle an article to be tied; means to move said carrier members to overlapping relation with each other and said sleeve shafts in substantially abutting relation to each other, and to move said wire strands about the free ends of said carrier members and into other sleeve shafts; and means to cut said wire strands at the free ends of said members when moved to overlapping relation whereby upon rotation of said sleeve shafts the free ends of said wire will be twisted together.

5. In a wire tying device, complemental slidably mounted carrier members; wire tying fingers rotatably mounted on said carrier members; means to extend a wire across the free ends of said carrier members; and means to move said carrier members toward each other so that the wire extended across the end thereof will overlap the wire extended across the end of its complemental carrier member; means to frictionally engage the wire at the ends of said members when said members are moved to wire overlapping position; means to cut said wire upon the bringing together of said complemental carrier members; and means for rotating said wire tying fingers to twist the free ends of said wire together.

6. In a wire tying device, complemental slidably mounted carrier members adapted to be moved into cooperative wire tying position; a supply of wire for each carrier member; means on each member to engage and retain a portion of said wire about the free end of said member when said members are moved to wire tying position; means to cut the wire at the free ends of said members; means to frictionally engage the wire at the free ends of said members; and means on each of said members to engage a cut wire end of its complemental member to twist abutting cut wire ends together.

7. In a device for tying wire, a plurality of wire strands extending from supply sources; means to cut said wire strands; means to frictionally engage the cut ends of said wire strands; and a wire tying element for each wire strand including wire tying means adapted to engage a wire strand from a supply other than the supply for such element and to twist the same about a wire strand from its supply.

8. In a wire tying device, supporting members; carrier members slidably mounted on said supporting members and adapted to be brought into abutting position with each other where the free ends thereof slightly overlap each other; a plurality of rollers at the free ends of each of said carrier members; wire supply reels for each carrier member; a sleeve shaft mounted on opposite sides of each of said carrier members, one of said

- sleeve shafts on each of said carrier members having extended therethrough wire from said wire supply reels; a tensioned wire engaging plate mounted on each of said carrier members; 5 means to move said carrier members into abutting and slightly overlapping position whereby said wire from said supply reels will be moved about said rollers and brought into engagement with said tension plate on an opposite carrier member; cutting means associated with said carrier members to cut said wires when said carrier members are moved into overlapping relation; wire tying fingers on each of said sleeve shafts; and means for rotating said wire tying fingers 10 when said carrier members have been moved to cut said wires and thereby twist the free ends of said wires together.
9. The combination with a baling press, of means for feeding a wire across the baling chamber from each side thereof; means for moving said wires along said baling chamber and about a bale formed therein; means for causing said wire to encircle said bale and to be brought in slightly overlapping position; means to cut said wire when in overlapping position; and a plurality of wire engaging fingers arranged to engage with and intertwist the free ends of said wire so as to leave a wire tied about said bales and across said baling chamber.
10. In a baling press having a compression chamber and a baling chamber; a compression plunger having in its forward face a transverse slot; an oscillatory member mounted in said slot and provided with a longitudinal slot; means extending from said oscillatory member and cooperating with cam means in said compression chamber to oscillate said member; wire twisting mechanisms arranged at opposite sides of said compression chamber; a wire extending from a supply of wire for each of said wire tying mechanisms; means to move said wire tying mechanisms toward each other into said longitudinal slot; and means to operate said wire twisting mechanisms to engage and twist together, wire from opposite supply spools, when said wire twisting mechanisms have been inserted in said longitudinal slot.
11. In a baling press having a compression chamber and a baling chamber; a compression plunger having in its forward face a transverse slot; an oscillatory member mounted in said slot and provided with a longitudinal slot; means extending from said oscillatory member and cooperating with cam means in said compression chamber to oscillate said member; wire twisting mechanisms arranged at opposite sides of said

compression chamber; a wire extending from a supply of wire for each of said wire tying mechanisms; means to move said wire tying mechanisms toward each other into said longitudinal slot; wire cutting and gripping means associated with said wire twisting mechanisms; and means to operate said wire twisting mechanisms to engage and twist together wire, from opposite supply spools, when said wire twisting mechanisms have been inserted in said longitudinal slot. 10

12. In a wire tying device, the combination of spools of wire having the free end portions of the wires joined together and extended across a passage-way in which an article to be tied is moved against said wires; and means cooperating with the wire from each spool of wire to form a loop of such wire between the article to be tied and the supply reel and operative to extend the bases of such loops across each other; means to cut said wires at the bases of said loops; and means to twist the cut ends of said wires together so as to leave a wire tied about said article and the free ends of the wires from the supply reels tied together. 15

13. In a wire tying device, the combination of supply reels of wire having the free end portions of the wires joined together and extended across a passage-way in which an article to be tied is moved against said wires; and means cooperating with the wire from each spool of wire to form a loop of such wire between the article to be tied and the supply reel; means to frictionally engage said wires at the bases of said loops; means to cut said wires at the bases of said loops; and means to twist the cut ends of said wires together so as to leave a wire tied about said article and the free ends of the wires from the supply reels tied together. 20

14. The combination with a passage-way in which an article to be tied is moved, of a wire supply on each side of said passage-way; means positioning a wire from each supply in front of each article to be tied across said passage-way with the ends of the wires from each supply united; means to move said article to be tied against said wires so as to extend the same about said article and along said passage-way; means for forming a loop in each wire between the article to be tied and said wire supply and behind said article to be tied; means to cut said wires at the bases of said loops; and means to twist the cut ends of said wire together so as to leave a wire tied about the article to be tied and united wires from said supplies extending across said passage-way. 25

FRED J. TRIMBLE. 30
